UNITED STATES PATENT OFFICE.

WILLIAM W. WEIR, OF ALAMEDA, CALIFORNIA, ASSIGNOR TO MAJESTIC ELECTRIC APPLIANCE COMPANY, INCORPORATED, OF SAN FRANCISCO, CALIFORNIA, A CORPORATION OF CALIFORNIA.

WAFFLE IRON.

Application filed February 21, 1924. Serial No. 694,232.

To all whom it may concern:

Be it known that I, WILLIAM W. WEIR, a citizen of the United States, and a resident of the city of Alameda, in the county of Alameda and State of California, have invented a new and useful Waffle Iron, of which the following is a specification.

This invention relates to a device for cooking waffles, and more particularly to an electrically heated iron of that character.

It is one of the objects of my invention to improve in general the mode of construction and operation of such waffle irons.

It is another object of my invention to prevent undue waste of heat by conduction or radiation; and instead, to make it possible to conduct substantially all of the heat developed by the heating elements, to the waffle molds.

It is still another object of my invention to make it possible to utilize both sides of the grids, whereby waffles may be cooked on one side, and cakes on the other. In this connection my invention contemplates the use of grids which are conveniently arranged for ready reversal in the iron. Since these irons are usually in the form of hinged sections which may be opened to present both of the reversible plates or grids for use as hot plates, the upper section when opened is designed to rest in a substantially horizontal position, and to be supported therein by the handle.

My invention possesses other advantageous features, some of which, with the foregoing, will be set forth at length in the following description, where I shall outline in full that form of the invention which I have selected for illustration in the drawings accompanying and forming part of the present specification. Although I have shown in the drawings but one embodiment of my invention, I do not desire to be limited thereto, since the invention as expressed in the claims may be embodied in other forms also.

Referring to the drawings:

Figure 1 is a side elevation of a waffle iron embodying my invention;

Fig. 2 is a sectional view taken through the center of the iron shown in Fig. 1;

Fig. 3 is a sectional view, taken along plane 3—3 of Fig. 2;

Fig. 4 is a sectional view, taken along plane 4—4 of Fig. 3, and showing the hinge construction;

Fig. 5 is an elevation of the iron shown in Fig. 1, taken from the right of that figure, with the cover plates for the hinge removed;

Fig. 6 is a fragmentary sectional view, illustrating the construction of the terminals for the heating elements;

Fig. 7 is a perspective view of one of the cover members used in connection with the hinge construction; and

Fig. 8 is a sectional view, taken along plane 8—8 of Fig. 3, and illustrates the manner in which the heating element is supported.

The waffle iron comprises a lower hollow section 11, which serves as a receptacle for the parts of one mold, and an upper hollow section 12, accommodating the parts for the other mold. In the present instance these sections are shown as circular in form, and having slightly domed contours for enhancing the good appearance of the iron. The lower half 11 has a cylindrical wall 13, which encompasses the lower mold 14 (Fig. 2). This mold substantially entirely covers the open side of the section 11, and is shown as having the usual projections 15 which form depressions in the finished waffle. Around the edge of the plate or mold 14 there is formed a depression or groove 16, shown in dotted lines in Fig. 2, for catching any excess batter that may be placed in the mold. Furthermore, the plate or mold 14 is so supported in the section 11 that its edge projects slightly above the beaded lip 17 of the shell. In this way, whatever batter finds its way out between the two mold sections, will pass over this lip 17 and will not run down on the wall 13.

One of the features of my invention is the manner in which the mold 14 is held in the shell 11, whereby said mold may be reversed in the section 11 to expose its lower, smooth surface 18, on which hot cakes or other similar food articles may be cooked. For this purpose, the mold 14 fits loosely enough in the section 11 to permit ready removal. This loose fit also insures against material heat loss by conduction from the

plate 14 to the section 11. At one point, the mold 14 is provided with a pin or other projection 19 (Fig. 2) which may be projected through the wall 13. At another peripheral point, substantially opposite the pin 19, a headed pin or screw 20 is provided, and projects outwardly with respect to the mold 14, and is received in the appropriately formed slot 21 in the lip 17 of the section 11. In order to prevent accidental or unintentional removal of the waffle grid 14, a thumb button 22 is provided, slidably mounted on the projection 20 and urged as by spring 23 toward the lip 17. In order to provide space for this spring between the head of projection 20 and the button 22, this button is counterbored as illustrated in Fig. 2. Furthermore, the inner portion of the button is cut away to conform to the beaded lip 17. The engagement of this portion of the spring-pressed button with the lower portion of the lip causes this lip to act as a catch and prevents effectively any accidental removal of the grid plate 14; yet by pulling outwardly on the button 22, it may be readily freed, and the plate may be easily lifted by the button 22, at least far enough to permit withdrawal of pin 19 from the opposite side. The reverse process of insertion is readily apparent from the foregoing.

The reversibility of plate 14 makes it necessary to provide a stationary heating device that operates substantially equally as well for either position of the plate 14. In the present instance, I secure this result by providing a large area of contact between the bottom side of plate 14 and a flat, disc-like heating element 24. This surface contact is produced by gravity; the plate 14 dropping as far as it is permitted, onto the top of the element.

I preferably construct the disc-like metallic member making up the casing for the element 24, from metal of high conductivity, such as aluminum. A shallow depression 25 is formed in one side of the element, which serves to accommodate the flat convoluted coil of resistance wire 26. This coil serves as the heating means when properly connected to a source of electricity. It is insulated by the aid of a pair of insulation discs 28, preferably of mica. The coil is preferably wound in the manner shown, back and forth to produce a zig-zag or serpentine configuration. The wire may usually be of such size that it is pliant, and there is no difficulty in adjusting the shape of the coil after winding to any desired flat curve, as for instance the circle shown in Fig. 3. The entire element 24 is fastened to a supporting plate 29, as by the aid of the screws 30. This supporting plate has a slightly raised edge 31, forming a guide for the element 24. This support is fastened at

this edge 31 in a few places as by the screws 34, to the clips 32 (Fig. 8) which are held as by welding to the inner surface of wall 13. As shown clearly in Fig. 3, the support 29 is of slightly smaller diameter than the inner diameter of section 11, so that there is no opportunity for material direct conduction of heat from the support to this section. However, in order to facilitate centering of the support 29, it is provided with a few projections 33, arranged to contact with the inner surface of the wall 13.

The support 29 also serves to carry terminal posts 35 which are insulatingly held in apertures located in small supplementary depressions. From these posts, leads 36 extend through insulating bushings 37 (Fig. 3) in support 29, and connect to the ends of the coil 26. The bushings 37 are located in depression in support 29, similar to those associated with the terminal posts 35.

The mode of leading in the connections from an external point involves the use of a pair of posts 38 (Fig. 6) which are adapted to be plugged into a cooperating detachable plug of the usual character. In order to make these posts accessible, the section 11 is cut away as indicated at 39, Fig. 6. A tubular guide for the plug is formed of an internally extending hood 40, and an external tube-like member 41 registering with and forming a continuation of the inner hood 40. This hood has an end wall 42 upon which the posts 38 are insulatingly supported. The hood 40 and member 41 may be fastened to the shell section 11 by the aid of appropriately formed flanges 43 and 44, and of fastening devices passing through these flanges and the wall of section 11. There is a likelihood that some heat will be developed by the current flowing through the contacts between posts 38 and the cooperating plug, especially if there be appreciable contact resistance. This heat may in fact be so great as to cause the metal of guide member 41 to become uncomfortably hot. In order to reduce this heating as much as possible, I provide one or more apertures 45 in the guide member 41, so as to permit a better air circulation in and through this guide.

The upper shell section 12 houses devices quite similar to those described in connection with the lower section 11. There is a support 29 for a heating element 24, held inside the shell section in a similar manner to that of the lower support 29. The upper waffle mold plate 46 is substantially identical with the lower plate 14, and is reversibly fastened to the shell section 12, by the aid of a pin 47, a projection 48 engaging in a slot in the lip of the section.

Both sections 11 and 12 have hinge leaves or lugs 49 and 50, forming the legs of substantially U-shaped members 52 and 53,

which are fastened externally respectively to the lower and upper sections. The fastening may be in the form of rivets 51 (Fig. 4) or by welding between the bottom of the 5 **U** and the section walls. The cooperation between the lugs is most clearly illustrated in Fig. 4, where it is seen that that pair of lugs 50 and 49 which are inside of the others are provided with slots 54; the hinge 10 pins 55 pass through these slots. This slot serves to allow play between the two section 11 and 12. This play is needed to ensure that the top mold plate 46 will rest evenly over the lower plate 14 with the iron 15 closed. The parts are purposely so proportioned that the entire upper section 12 and its associated parts rest by gravity on the lower section. In this way there is a certainty that intimate contact between the 20 heating elements 24 and the mold sections 14 and 46 is maintained. The proportioning of the parts for this effect involves making the slots 54 in the hinge lugs 49 and 50 long enough, and also the slots in the lips 25 17, which slots accommodate the projections 20 and 48.

The connections between the upper heating coil 26 and the terminal posts 38, whereby said coil is placed in circuit, are effected 30 by the aid of insulated leads, indicated diagrammatically by the numeral 56 in Figs. 2, 3 and 4. These leads pass through an aperture 57 (Fig. 4) formed through the wall of upper section 12 and the **U**-shaped 35 member 53. From there the leads enter the lower section 11 through a similar aperture 58 and are there appropriately connected in circuit. Enough extra length is provided for these leads to permit the maximum relative movement between the hinged sections. 40

In order that the portion of leads 56 which extend outside of the shell sections 11 and 12 and between apertures 57 and 58, be concealed, I preferably provide cover 45 members such as 59 and 60 (shown in greater detail in Fig. 7). These members cover the space formed between the pairs of hinge lugs 49 and 50, and are attached respectively to the upper hinge lugs 50 and the lower 50 lugs 49. The attachment in this instance consists of flaps or corners 61, one on each side of the member 59 or 60, and extending in a direction substantially parallel to that of the lugs 49, 50. These two corners 55 are spaced just far enough apart on the body or cover portion of the member 59 as to be capable of being sprung between these hinge lugs. For producing the desired flexibility or resiliency of these flaps, the member 59 is made from sheet metal of the proper characteristics. In order to keep the member 59 still more securely in place, I provide a small projection 62 on each flap 61, as by stamping; which is adapted to engage in a recess or depression 63 (Fig. 4)

appropriately formed on the inside of each hinge lug.

The main body portion of the member 59 extends between the lugs 50 or 49 of the shell section with which it is associated, 70 and carries a tubular extension 64. This extension is approximately one-half as long as the distance between the ears or flaps 61, and is arranged to register with the circular-shaped extremities of the hinge lugs, so 75 as to be substantially coaxial with the hinge pins 55. These tubular extensions have an open portion, making them not quite complete cylinders, whereby the wires 56 may be readily slipped through this open portion and carried through the extensions. The relative movement of the two hinged sections 11 and 12 does not, however, serve to expose this interruption or break in the tubes, since this break is turned always 80 toward the inside of the iron. Furthermore, the two extensions 64 are reciprocally spaced on the upper and lower sections, whereby they aline to form a substantially 85 continuous tubular conduit between the 90 hinge lugs. This feature is best disclosed in Fig. 3. It is also to be noted that the pins 19 and 47 which serve as one point of support for the mold plates 14 and 46, extend to that portion of the shell sections which is 95 covered by the members 59; in this way the apertures for accommodating these pins are effectively concealed.

Another feature of my invention resides in the nature of the support for the entire iron. In this support, the endeavor is made to prevent heat loss by conduction to the greatest extent, yet with the aid of relatively simple and inexpensive parts. For this purpose, the base 65 has a double-walled, sheet 100 metal construction. The lower portion 67 has a plurality of stamped-out projections 66 on which the device rests, while the upper portion 68 is spaced therefrom and has a saucer-like form to catch whatever drip of 105 batter may occur between the molds. At the center of this member 68, there is an open column-like support 69, formed preferably integrally with the member 68, and on which the lower section 11 is supported. For this purpose a flat plate 70 is placed on top of the support 69, resting on a curved portion 71 thereof, so as to have a very narrow band 110 of contact therewith. This plate in turn also carries a curved, turned up edge 72 on which the bottom of section 11 rests. It is however spaced from the plate 70, so that only a very narrow band of contact is again 115 established. In this way, only a negligible amount of heat can be conducted from the section 11 through these areas of contact. A central bolt 73 serves to fasten the parts 120 11, 70 and 67 together. In order to prevent relative turning of the section 11 and plate 70, there is another mechanical connection 125 130

between them, such as that secured by the slot 74 in the section 11, and the stamped-up projection 75 on the plate 70.

When the iron is opened up for the purpose of filling the molds with batter or of making hot cakes, it is necessary to support the upper section in a substantially horizontal position. For manipulating the upper section 12, and also for providing such a support, there is a handle 76 which has ends 77 adapted to rest on the table or other support when the iron is open. This handle is made from a good heat insulator, and is spaced at the proper height from the section 12 by the aid of a U-shaped strap 78, the bottom of which is located within the shell 12. The legs 79 of this strap pass through appropriate slots in the section 12, and at their free extremities are fastened as by screws 80 to the ends of the handle 76. Appropriate fastening devices, such as rivets 81 serve to hold the member 78 to the section 12.

In order to provide a supplementary means for manually moving the upper section 12 about its hinges, and also to improve the appearance of the device, an insulation knob or button 82 at the very peak of section 12 is provided. Since many kinds of insulation material have a decided odor when sufficiently heated, I aim to support this button in such a way as to prevent any material conduction of heat thereto from the section 11. For this purpose, as most clearly shown in Fig. 2, I provide a seat 83 of sheet metal, having a turned-down edge 84 which rests on top of the section 12 and contacts only on a narrow band therewith. The upper part of this seat has a depression with sloping sides 85. On these sides the button 82 is supported at its edge. The bottom of the button however, is spaced from the bottom of the depression in the seat 84, so that there is a narrow band of contact between the button 82 and its seat. A bolt 86 passes through the wall of section 12 and the seat 84 for fastening the button securely in place. This bolt is preferably fixed in the button before assembling. Appropriate supplementary mechanical connections are also provided to prevent rotation of the seat 84 and of button 82. These connections consist of projection 87 on seat 84 engaging a slot 88 in section 12, and a similar projection 89 on the other side of the seat 84, engaging a slot 90 in the button 82.

The mode of operation of the waffle iron either to cook waffles or hot cakes is apparent from the foregoing description. The iron may either be opened out completely and the grids reversed to form a pair of heated flat plates which may be used in an obvious fashion. In this condition the handle 76 rests on the table or other support on which the iron is placed. The support af-

firmed by the handle is rigid enough for all purposes, since it is far from the pivot point and presents two points of contact at its ends 77 which are disposed a considerable distance apart.

I claim:

1. In an electric cooking utensil, a receptacle, and a support for said receptacle, comprising a hollow double-walled metallic base.

2. In an electric cooking utensil, a receptacle, and a support for said receptacle, comprising a hollow double-walled metallic base, said base having an area of contact with the receptacle of small amount, whereby conduction of heat to the base is substantially prevented.

3. In an electric cooking utensil, a receptacle, and a support for said receptacle, comprising a hollow double-walled metallic base, said base having a plurality of projections serving as feet stamped out on its bottom side.

4. In an electric cooking utensil, a receptacle, and a support for said receptacle, comprising a hollow double-walled metallic base, the upper wall of said base having a supporting column upon which the receptacle rests, the contour of said base and receptacle being such that there is a relatively small area of contact to permit heat conduction from one element to the other.

5. In an electric cooking utensil, a receptacle, a hollow double-walled metallic base for said receptacle, the upper wall of said base having a projection serving as a support for said receptacle, and a plate on said projection having a thin band of contact with the projection, said plate having a curved portion arranged to contact with the bottom of the receptacle, whereby only a thin band of contact is provided between the plate and the receptacle.

6. In an electrically heated utensil, a hollow shell section, a flat heating element fastened to the inside of the section, and a plate to which heat is to be imparted resting gravitally and loosely against said element.

7. In an electrically heated utensil, a hollow shell section, a flat heating element fastened to the inside of the section, a plate to which heat is to be imparted resting gravitally against said element, and means whereby said plate may be readily reversed to present either side for use, comprising a pin and aperture connection between the plate and the section, and a slot and pin connection at another point of the plate, said slot and pin connection having vertical play to permit vertical movement of the plate to contact with the heating element.

8. In an electrically heated utensil, an upper and a lower shell section, a hinge connection between the sections, a heating element fastened into each of the sections, and

70

- plates adapted to contact gravitally and loosely with said heating elements and arranged, when the sections are closed, to be next to each other, the hinge connection being such as to permit the upper section to rest gravitally and loosely on the lower and to permit the plates and the heating elements to form a series of gravitally but loosely contacting parts.
- 10 9. In an electrically heated cooking utensil, an open shell section, a reversible plate supported in said section, said plate having both sides capable of use for cooking, and a detachable connection between the plate and the section, comprising a projection extending from the plate and arranged to be accommodated in a slot in the lip of the section, and a button slidably arranged on said projection and resiliently urged toward the outer surface of the section.
- 10 10. In an electrically heated cooking utensil, an open shell section, a reversible plate supported in said section, said plate having both sides capable of use for cooking, and a detachable connection between the plate and the section, comprising a projection extending from the plate and arranged to be accommodated in a slot in the lip of the section, and a button slidably arranged on said projection and resiliently urged toward the
- outer surface of the section, said lip projecting to form a catch engaging the button.
11. In an electrical cooking utensil, an upper and a lower section hingedly connected together, and means for supporting the upper section in open horizontal position, comprising a handle rigidly attached to the other section and near the edge thereof remote from the hinge connection.
12. In an electrical cooking utensil, a pair of sections, hinge lugs on each section whereby they may be hingedly connected together, there being two for each section, spaced some distance apart, and cover plates between the lugs, said plates having ends frictionally engaging the lugs and sprung therebetween.
13. In an electrical cooking utensil, a pair of sections, hinge lugs on each section whereby they may be hingedly connected together, there being two for each section, spaced some distance apart, and cover plates between the lugs of each section, said plates being of resilient material and having flaps at their ends adapted to engage frictionally with the lugs between which the cover plates are sprung.

In testimony whereof, I have hereunto set my hand.

WILLIAM W. WEIR.
